UNITED STATES PATENT OFFICE.

HELENE V. A. LORING, OF CHICAGO, ILLINOIS.

DESIGN FOR A PLAYING-CARD.

56,072.

Specification for Design.

Patented Aug. 10, 1920.

Application filed December 29, 1919. Serial No. 348,189. Term of patent 14 years.

To all whom it may concern:

Be it known that I, HELENE V. A. LORING, a citizen of the United States, residing at Chicago, in the county of Cook and State of Illinois, have invented a new, original, and ornamental Design for Playing-Cards, of which the following is a specification, reference being had to the accompanying drawing, forming a part thereof, and in which—

Fig. 2, is a face view of another form of card embodying the design.

I claim:—

The ornamental design for a playing card, as shown.

HELENE V. A. LORING.

In presence of—

JOSHUA R. H. POTTS,
B. G. RICHARDS.
